MULTIPLE PISTON ENGINE

Clinton David Town, Portland, Oreg.

Application December 13, 1934, Serial No. 757,261

9 Claims. (Cl. 123—51)

The object of my invention is to provide an engine having a single crank throw and a connecting rod operatively joined thereto with means for giving opposed reciprocal action to a plurality of pistons defining one or more combustion chambers in the cylinder of said engine. That is, my invention is directed toward the simplification of a multiple piston engine in which the pistons reciprocate in opposite directions and define between them a combustion chamber and which action can be attained by a single connecting rod and a single crank throw.

The object of my invention is attained in an internal combustion engine having a cylinder element defining one or more combustion chambers, each arranged between two opposed pistons. If more than one combustion chamber is provided, one piston preferably is common to two combustion chambers. A connecting rod is joined to one crank throw of the crank shaft of said engine and is bifurcated and preferably is directly joined to the ends of the piston pin of one piston. A pair of reciprocating straps is similarly joined to the ends of the piston pin of said piston and the pin of another piston spaced therefrom. An intermediate piston is operatively connected to the connecting rod through a pair of levers pivotally mounted adjacent their ends, so that opposite movement will be given said intermediate piston.

To eliminate all tendency toward distortion of said members, I preferably arrange said levers not only to join both ends of the piston pin of said intermediate piston, but also to encircle the cylinder and thus eliminate any tendency which would distort any of said members upon axes normal to the axis of the piston pin of the intermediate piston, as well as about the axis of the latter.

The details of my invention are hereinafter described with reference to the accompanying drawing in which:

Fig. 1 is a more or less diagrammatic plan view of a simple form of engine embodying my invention, looking downwardly upon the pivot axis of the levers joining the piston;

Fig. 2 is an elevation of said engine viewing the latter in a plan extending at right angles to said pivot axis;

Fig. 3 is a more or less diagrammatic sectional view illustrating the position of the pistons in the cylinder when the contents of one combustion chamber are compressed to maximum degree, and the contents of the other combustion chamber are fully expanded; and

Fig. 4 is a sectional view similar to Fig. 3, in which the conditions of said combustion chambers are reversed.

My invention is illustrated as embodied in an engine of simple form. Said engine includes a cylinder *a* carried by a base *b*. The crank *c* is journaled in bearings *d*, also carried by said base. The single crank throw *c'* of said crank engages a connecting rod *e*. Said connecting rod is preferably bifurcated at *e'*, which bifurcated end *e'* straddles the end of the cylinder *a* and engages the ends of the piston pin *f'* extending through the piston *f*.

Lying in spaced relation along the cylinder are pistons *f*, *g*, and *h*. The piston pins *f'*, *g'*, and *h'*, in their respective pistons, extend laterally therefrom through ported sections of the cylinder *a*, the ported sections being *a'*, *a2*, and *a3* for the piston pins *f'*, *g'*, and *h'* respectively.

Connecting the piston pins *f'* and *h'* are a pair of straps *i* lying at opposite sides of the cylinder. Said straps are of fixed length and are connected to said two piston pins, and thus the piston travel of the pistons *f* and *h* are exactly the same and are in synchronism with each other. The straps *i* are slotted at *i'* to pass about the piston pin *g'* without engagement therewith. The piston pin *h'* is connected to the piston pin *g'* through a pair of pivoted levers *j* and *k* and links *l* and *m*. The levers *j* and *k* are crossed substantially at their middle, and at the point of intersection are pivotally mounted upon laterally extending studs *n* diametrically opposed and extending laterally from the opposite sides of the cylinder *a*. The levers *j* extend exteriorly of the levers *k* and said levers are arranged in pairs which substantially encircle the cylinder, as is disclosed in Fig. 2. The end of one pair of levers *j* is connected to one end of the piston pin *g'* through one pair of links *l*. The opposite end of said levers *j* are connected to the opposite end of the piston pin *h'* through a pair of links *m*. The levers *k* are similarly secured to the opposite ends, respectively, of the piston pins *g'* and *h'* through pairs of links *l* and *m*.

The levers *j* and *k* are arranged in pairs substantially encircling the cylinder so that there will be no lateral thrust exerted upon the studs *n*, or upon the ends of the piston pins *g'* and *h'*. Likewise, said levers are connected to both ends of the piston pins *g'* and *h'*, respectively, through links *l* and *m*, so that both ends of the piston pin will exert similar thrusts against the ends of the other piston pin to which they are joined, the action being, however, diagonally through the

45

links *l* and *m*. The levers *j* and *k* are connected to both ends of the piston pins *g'* and *h'*, respectively, through links *l* and *m*, so that both ends of the piston pin will exert similar thrusts against the ends of the other piston pin to which they are joined, the action being, however, diagonally through the

50

55

studs *n* and move the opposite ends of the piston pins through said pivoted levers.

A combustion chamber *o* is defined between the pistons *f* and *g* and a similar combustion chamber 5 *p* is defined between the pistons *g* and *h*.

The operation of my engine is as follows:

When the engine is arranged as is shown in Figs. 1 to 3, inclusive, the crank throw *c'* has caused pistons *g* and *h* to be moved apart to their 10 maximum degree, and the pistons *f* and *h* to be moved toward each other, so that the combustion chamber *o* lying between them is restricted to its minimum compass. When the crank throw is rotated 180° pistons assume the positions shown 15 in Fig. 4. The rotation of the crank shaft to this position causes the lever *k* to be rocked clockwise and the lever *j* to be rocked counter-clockwise to a degree sufficient to move the pistons *g* and *h* toward each other, as is indicated in Fig. 4.

20 Inasmuch as the pistons *f* and *h* have the same piston travel and the piston *g* has a similar piston travel in the opposite direction, the pistons *f* and *g* are spread apart after said rotation until they 25 assume the position shown in Fig. 4, which is substantially the reverse of that shown in Fig. 3. The continued rotation 180° will cause said parts to assume their original positions.

My invention is not intended to be limited to the exact structure illustrated in an engine having 30 three pistons and two combustion chambers. As is apparent to a person skilled in the art, it is 35 equally adapted to an engine having more pistons and, correspondingly, more combustion chambers by duplicating the parts and extending the cylinder. Likewise, if it is desirable to have only 40 two pistons and a single combustion chamber, the piston *f* could be eliminated, for example, and the connecting rod secured directly to the piston pin *h'* through the straps *i*, or by reversing said parts 45 end for end could be directly secured to the piston pin *h'*.

I claim:

1. An internal combustion engine including a cylinder element defining a combustion chamber 45 provided with two opposed pistons, a crank shaft and a connecting rod direct connected to the wrist pin of one of said pistons, and the other piston being operatively connected with said first mentioned piston thru a lever pivotally mounted 50 intermediate its ends and joined to the wrist pin of said last mentioned piston, which pin extends laterally through the walls of the cylinder element.

2. An internal combustion engine including a cylinder element defining a combustion chamber 55 provided with two opposed pistons, a crank shaft and a connecting rod direct connected to the wrist pin of one of said pistons, the other piston being operatively connected with said first mentioned piston 60 thru a lever pivotally mounted intermediate its ends and upon the cylinder, said last mentioned piston, which pin extends laterally through the walls of the cylinder element.

3. An internal combustion engine including a cylinder element defining a combustion chamber 65 provided with two opposed pistons, a crank shaft and a connecting rod operatively connected to one of said pistons, the other piston being operatively connected with said first mentioned piston 70 thru a pair of levers pivotally mounted intermediate their ends upon the cylinder, and lying at opposite sides thereof.

4. An internal combustion engine including a cylinder element defining a combustion chamber 75 provided with two opposed pistons, a crank shaft

and a connecting rod operatively connected to one of said pistons, the other piston being operatively connected with said first mentioned piston thru a lever pivotally mounted intermediate its ends, said cylinder being ported, a piston pin extending laterally from each piston thru the ported walls of the cylinder, and a link element pivotally joining the ends of each of said pins to the ends of said lever. 5

5. An internal combustion engine including a cylinder element defining a plurality of combustion chambers, each provided with two opposed pistons, one piston being common to both combustion chambers, a crank shaft and a connecting rod operatively connected to one piston in 10 each combustion chamber, the other piston in each of the combustion chambers being operatively connected with said first mentioned pistons thru a lever pivotally mounted intermediate its 15 ends.

6. An internal combustion engine including a cylinder element defining a plurality of combustion chambers, each provided with two opposed pistons, one piston being common to both combustion chambers, a crank shaft and a connecting rod operatively connected to one piston in each combustion chamber, the other piston in each of the combustion chambers being operatively connected with said first mentioned pistons 20 thru a pair of levers pivotally mounted intermediate their ends, upon the cylinder, and lying at opposite sides thereof. 25

7. An internal combustion engine including a cylinder element defining a combustion chamber 30 provided with two opposed pistons, a crank shaft and a connecting rod operatively connected to one of said pistons, the other piston being operatively connected with said first mentioned piston thru a pair of crossed levers pivotally mounted 35 intermediate their ends, said cylinder being ported, a piston pin extending laterally from each piston thru the ported walls of the cylinder, and means pivotally joining the ends of each of said pins to the ends of said levers. 40

8. An internal combustion engine including a cylinder element defining a combustion chamber 45 provided with two opposed pistons, a crank shaft and a connecting rod operatively connected to one of said pistons, the other piston being operatively connected with said first mentioned piston 50 thru a pair of crossed levers pivotally mounted intermediate their ends, said cylinder being ported, a piston pin extending laterally from each piston thru the ported walls of the cylinder, and a link element pivotally joining the ends of each 55 of said pins to the ends of said levers.

9. An internal combustion engine including a cylinder element defining a plurality of combustion chambers, each provided with two opposed 60 pistons, one piston being common to both combustion chambers, a crank shaft and a connecting rod operatively connected to one piston in each combustion chamber, the other piston in each of the combustion chambers being operatively 65 connected with said first mentioned pistons thru a pair of crossed levers pivotally mounted intermediate their ends, upon the cylinder, and lying at opposite sides thereof, said cylinder being ported, a piston pin extending laterally from each 70 piston thru the ported walls of the cylinder, and means pivotally joining the ends of each of said pins to the ends of said lever. 75
